UNITED STATES PATENT OFFICE.

RUDOLPH LIEBMAN, OF NEW YORK, N. Y.

DESIGN FOR A CAMPAIGN BUTTON.

SPECIFICATION forming part of Design No. 18,574, dated August 28, 1888.

Application filed July 26, 1888. Serial No. 281,131. Term of patent 3½ years.

To all whom it may concern:

Be it known that I, RUDOLPH LIEBMAN, a citizen of the United States, residing at New York, in the county and State of New York, 5 have invented and produced a new and original Design for Buttons, of which the following is a specification, reference being had to the accompanying drawing.

The object of this design is to provide a 10 novel button, and is illustrated in the accompanying drawing, in which the figure is a plan view of the face of the button.

The leading features of the design consist in a button having on its face A the representation of a log cabin, *a*, from the roof *b* of which 15 rise a chimney, *c*, and a flag-staff, *b*, carrying

a flag, *d*. At the ends of the cabin, trees *e*, *f* may be placed.

What I claim as new, and desire to secure by Letters Patent, is—

The design for a button having its face provided with the log cabin *a*, chimney *c*, and flag-staff *b*, carrying the flag *d*, substantially as shown and described.

In testimony whereof I have hereunto set my 25 hand and seal in the presence of two subscribing witnesses.

RUDOLPH LIEBMAN. [L. S.]
